UNITED STATES PATENT OFFICE.

MILTON A. ROBERTS, OF BATTLECREEK, MICHIGAN.

WALL-PAPER-PASTING MACHINE.

SPECIFICATION forming part of Letters Patent No. 777,433, dated December 13, 1904.

Application filed March 17, 1904. Serial No. 198,650. (No model.)

To all whom it may concern:

Be it known that I, MILTON A. ROBERTS, a citizen of the United States, residing at Battle-creek, in the county of Calhoun and State of Michigan, have invented a new and useful 5 Wall-Paper-Pasting Machine, of which the following is a specification.

This invention relates to the art of hanging wall-paper, and has for its object to facilitate 10 the trimming, cutting into strips, and pasting the paper prior to its application to walls and ceilings.

It is an important object to arrange the elements of the present apparatus in position 15 for convenient adjustment, in originally fitting the wall-paper in the apparatus, and in the adjustment of the cutter.

Another object of the invention is to provide for automatically actuating the paste- 20 applying device and the cutter by the action of drawing the paper from the apparatus to the ordinary paste-table, where the paper is cut up into lengths in the usual manner.

It is furthermore designed to arrange the 25 apparatus for convenience in transportation, and in this connection it is particularly designed to prevent the spilling of paste when the apparatus is being carried from place to place, whereby it is not necessary to remove 30 the paste after the work has been accomplished and to refill the paste-tank each time the apparatus is put in operation.

With these and other objects in view the 35 present invention consists in the combination and arrangement of parts, as will be herein-after more fully described, shown in the accompanying drawings, and particularly pointed out in the appended claims, it being understood that changes in the form, proportion, 40 size, and minor details may be made within the scope of the claims without departing from the spirit or sacrificing any of the advantages of the invention.

In the drawings, Figure 1 is a top plan view 45 of a wall-paper-pasting apparatus embodying the features of the present invention. Fig. 2 is a longitudinal sectional view thereof. Fig. 3 is a detail sectional perspective view illustrating the mounting of the paper-cutter.

Like characters of reference designate corresponding parts in each and every figure of the drawings.

The frame of the present apparatus consists of a comparatively shallow and substantially rectangular box 1, having an open top. Located centrally within the box and extending entirely across the same is a supply tank or reservoir for containing a supply of paste. This reservoir is preferably made up of a rear transverse partition 2, a front partition 3, 55 somewhat shorter than the rear partition, and a top 4, which is located below the top edge of the box or frame. The rear partition projects somewhat above the top of the paste-reservoir, but terminates short of the top edge 60 of the box and has its upper rear edge beveled, as at 5, to form a paper-guide, as will herein-after appear.

As best indicated in Fig. 2 of the drawings, it will be seen that the supply-reservoir divides the box or casing into a rear paper-compartment 6 and a front working compartment 7 for the paste, communication being had from the supply-reservoir to the paste-chamber through the medium of one or more openings 70 8, formed through the lower edge of the front of the supply-reservoir. This arrangement of parts has a very important advantage in that when the apparatus is being transported with its front end uppermost the paste in the 75 working compartment 7 will run back into the supply-reservoir, whereby there is no danger of the paste being spilled and the apparatus may be conveniently handled. Moreover, when the apparatus is not in use it may 80 be stood up upon its rear end, whereby the paste in the working compartment is returned to the supply-reservoir, wherefore it is not necessary to remove the paste after the work of the apparatus has been completed. Moreover, when the paste has been run back into the supply-reservoir there is little or no evaporation, and the paste does not suffer any deterioration while standing in the supply-reservoir in the interval between interrupted operations of the apparatus.

Located within the paper-compartment 6 is a transverse roller 9, which is journaled in

the opposite sides of the box and is detachable therefrom for the convenient reception of a roll of wall-paper 10. A suitable paste-roller or rotatable paste-brush 11 is journaled 5 transversely in the paste-compartment 7 and is provided at one end with a suitable crank-handle 12 for convenience in initially rotating the brush.

The roll of wall-paper is disposed to feed 10 from its under side and is passed forwardly over and in frictional contact with the paper-guide 5, thence across the top of the paste-reservoir, and over the top of the paste-roller. In front of the paste-roller is a felt-covered 15 guide-roller 13, which has its opposite ends rearwardly journaled in suitable bearing-brackets 14, mounted upon the top edge of the box. After leaving the top of the paste-roller the paper passes beneath and thence 20 upwardly across the front and rearwardly across the top of the guide-roller 13, from which it passes rearwardly across the top of the apparatus to the usual pasting-table, where it may be cut up into lengths in the 25 usual manner. It will here be noted that as the paper is cut off and used by the paper-hanger additional paper may be had merely by drawing upon the free end of the paper, whereby the latter will be drawn off from the 30 roll 10 and passed across the paste-roller without other manipulation of the apparatus.

To insure an effective engagement of the paper with the paste-roller, I employ a tension or presser device consisting of a metallic 35 roller 15, lying adjacent to and in parallel relation with the rear side of the paste-roller, the opposite ends of this presser-roller being journaled in a swinging frame consisting of arms 15^a, lying above the opposite sides of 40 the box or casing 1, with their rear ends hinged to the top edge of the box, as indicated at 16. Normally the frame-arms 15^a lie upon the top edges of the box, whereby 45 the presser-roller 15 engages the upper side of the paper just prior to its engagement with the paste-roller, whereby the paper is maintained in intimate contact with the paste-roller.

In order that the edges of the paper may be 50 trimmed and also to provide for cutting the paper into longitudinal strips, I employ a cutter embodying a guideway made up of spaced parallel cross-bars 17, the opposite ends of which are connected to and carried by the 55 arms 15^a of the presser-frame and are disposed centrally above the top 4 of the paste-reservoir. Working between the cross-bars 17 is a block 18, which is capable of slidable adjustment from one end to the other of the 60 guideway and has its upper end projected above said guideway for convenience in adjusting the block. From the front and rear sides of the upper portion of the block 18 depend spring-clips 19, which incline outwardly

and downwardly and have their lower ends 65 working in grooves 20, formed in the tops of the cross-bars 17. A suitable knife-blade 21 projects from the lower end of the block 18, and a pad 22 is carried by the upper face of the top 4 of the paste-reservoir, said pad extending transversely of the apparatus and alined beneath the guideway. A suitable guide strip or flange 23 depends from the rear cross-bar 17, so as to engage the upper side of the paper and hold the same close to the 75 bed or table afforded by the top 4 of the paste-reservoir.

From the foregoing description of the cutting means it will be understood that the paper travels from the paper roll 10 over the 80 paper-guide 5, under the upper paper-guide 23, and thence between the pad 22 and the knife-blade 21, so that when the combined presser and cutter frame is in its lowermost normal position the point of the knife-blade will pierce 85 the paper, and thereby sever the same into strips when the paper is drawn through the apparatus. In adjusting the knife to trim the edges of the paper or to sever it into longitudinal strips the upper end of the knife-block is grasped and moved upwardly sufficient to disengage the knife-blade from the paper, after which the block is slid to any position upon the guideway and then forced downwardly to thrust the knife-blade through 90 the paper. The vertical play necessary for the adjustment of the knife-block is afforded through the depths of the slots 20, whereby the spring clips or fingers 19 may be moved up or down in the slots in addition to their 100 longitudinal movement therein, the frictional engagement between the spring-fingers and the walls of the slots being sufficient to hold the knife-blade down in engagement with the paper without the employment of any additional fastening means.

From the foregoing description it will be apparent that the parts of the present apparatus are compactly arranged, so as to take up comparatively little space, and are also arranged for convenience in manipulation. A very important feature of arrangement resides in locating the cutter between the paper roll and the paste-roller, whereby the paper is severed prior to the application of paste thereto, whereby the cutter cannot become clogged or choked by accumulations of paste thereon. Again, by locating the paste-supply reservoir between the paper roll and the paste-roller the top of this reservoir serves as a table or bed for the cutter, thereby permitting of a very compact and conveniently-arranged disposition of the parts of the apparatus.

In fitting the paper to the apparatus preparatory to pasting the same the combined 115 presser and knife frame is swung upwardly, as indicated by dotted lines in Fig. 2 of the drawings, whereby the top of the paste-reser-

voir is unobstructed, and the paper may be conveniently drawn across the same and then over the paste-roller, after which the frame is returned to its normal condition, so as to 5 hold the paper in proper engagement with the paste-roller. It is at this stage of the operation that the crank-handle 12 of the paste-roller is employed to rotate the roller, and thereby feed the free end of the paper beneath the guide-roller 13 until it can be grasped and drawn rearwardly over the guide-roller. From this statement it will be understood that the crank-handle 12 is not intended for the general manipulation of the apparatus, but 15 serves merely to initially feed the paper from the paste-roll sufficiently to enable its convenient engagement with the guide-roller 13, wherefore it will be found convenient to have the crank-handle removable in order that it 20 may not offer an objectionable obstruction to the paper-hanger.

Having thus described the invention, what is claimed, and desired to be secured by Letters Patent, is—

25 1. An apparatus of the character described, comprising a casing, an intermediate paste-supply reservoir dividing the casing into a working paste-compartment in communication with the supply-reservoir and a paper- 30 compartment, a paper-carrying roller mounted in the paper-compartment, and a paste-applying device coöperating with the working paste-compartment.

2. In an apparatus of the character described, a casing, and a paste-supply reservoir located intermediately within the casing and dividing the latter into a paper-compartment at one side of the reservoir and a working paste-compartment at the opposite side of the 40 reservoir, the wall of the reservoir adjacent the paste-compartment having an opening in the lower portion thereof to afford communication between the compartment and the reservoir, whereby paste may return from the 45 compartment to the reservoir when the casing is stood on end with the paste-compartment uppermost.

3. In an apparatus of the character described, a casing, a paste-supply reservoir located within the casing and dividing the latter into a paper-compartment and a working paste-compartment, means for supporting a paper roll in the paper-compartment, and a paste-applying device coöperating with the 50 paste-compartment, the top of the reservoir forming a support for the paper in its passage from the paper-compartment to the paste-applying device.

4. In an apparatus of the character described, a casing, a paste-supply reservoir dividing the casing into a paper-compartment and a working paste-compartment, means for supporting a roll of paper in the paper-compartment, a paste-applying device coöperat-

ing with the paste-compartment, the top of 65 the reservoir forming a support for the paper, and a cutter coöperating with the top of the reservoir as a bed.

5. In an apparatus of the character described, a casing, a paste-supply reservoir dividing the casing into a paper-compartment and a working paste-compartment, means for supporting a roll of paper within the paper-compartment, a paste-applying device coöperating with the paste-compartment, the top 70 of the reservoir constituting a support for the paper between the paper-compartment and the paste-compartment, and a cutter coöperating with the top of the reservoir as a bed and adjustable transversely across the 75 same.

6. In an apparatus of the character described, a casing, a paste-supply reservoir dividing the casing into a paper-compartment and a working paste-compartment, the top of 80 the reservoir constituting a support for the paper between the paper-compartment and the paste-compartment, and a cutter coöperating with the top of the reservoir as a bed and capable of being moved away from the 85 reservoir to permit application of paper to the apparatus.

7. In an apparatus of the class described, a casing, a paste-supply reservoir dividing the casing into a paper-compartment and a working paste-compartment, the top of the reservoir constituting a support for the paper between the paper-compartment and the paste-compartment, and a cutter coöperating with the top of the reservoir as a bed and capable 90 of adjustment across the reservoir and also of movement toward and away from the same to permit application of the paper to the apparatus.

8. In an apparatus of the character described, a casing, a paste-supply reservoir dividing the casing into a paper-compartment and a working paste-compartment, the top of the reservoir constituting a support for the paper between the two compartments, a swinging frame carried by the casing and working toward and away from the top of the reservoir, and a cutter carried by the frame and coöperating with the top of the reservoir as a bed.

9. In an apparatus of the character described, a casing which is open at its top, a paste-supply reservoir dividing the casing into a paper-compartment and a working paste-compartment, the top of the reservoir constituting a support for the paper between the two compartments, arms hinged to the top of the casing at opposite ends of the reservoir, a guideway connecting the arms, and a cutter working in the guideway and coöperating with the top of the reservoir as a bed.

10. In an apparatus of the character described, a casing, a paste-supply reservoir di-

viding the casing into a paper-compartment and a working paste-compartment, the top of the reservoir constituting a support for the paper between the two compartments, spaced 5 cross-bars disposed above the reservoir and provided in their upper faces with longitudinal grooves, and a cutter slidably adjustable between the cross-bars, coöperating with the top of the reservoir as a bed and provided 10 with spring-fingers slidable in the grooves of the cross-bars and capable of vertical movement therein.

11. In an apparatus of the character described, a casing having an open top, a paste-supply reservoir dividing the casing into a paper-compartment and a working paste-compartment, the top of the reservoir constituting a support for the paper between the two compartments, arms hinged to the top of the 15 casing and located at opposite ends of the reservoir, a guideway connecting the arms, and a cutter adjustably slidable upon the guideway and also adjustable vertically thereon and coöperating with the top of the reservoir 20 as a bed.

12. In an apparatus of the character described, a casing, a paste-supply reservoir dividing the casing into a paper-compartment and a working paste-compartment, the top of 30 the reservoir constituting a support for the paper between the two compartments, a paste-applying device coöperating with the paste-compartment, a frame hinged to the casing and capable of movement toward and away 35 from the top of the reservoir, a presser-roller carried by the frame in coöperative relation with the paste-applying device, and a cutter carried by the frame and coöperating with the top of the reservoir as a bed.

13. In an apparatus of the character described, a casing, a paste-supply reservoir dividing the casing into a paper-compartment and a working paste-compartment, the top of 40 the reservoir constituting a support for the paper between the two compartments, a paste-applying device coöperating with the paste-compartment, a swinging frame hinged to the top of the casing adjacent the paper-compartment and extending across the top of the 45 reservoir, a presser-roller carried by the free end of the swinging frame in coöperative relation with the paste-applying device, and a cutter carried intermediately by the frame and coöperating with the top of the reservoir as a 50 bed.

14. In an apparatus of the character described, a casing, a paste-supply reservoir dividing the casing into a paper-compartment and a working paste-compartment, the top of 55 reservoir constituting a support for the paper between the two compartments, a paste-applying device coöperating with the paste-compartment, arms hinged to the top of the 60

casing adjacent to the paper-compartment and extending across the reservoir, a presser- 65 roller carried by the free ends of the arms in coöperative relation with the paste-applying device, a pair of spaced cross-bars connecting intermediate portions of the arms and lying above the reservoir, the upper faces of the 70 cross-bars being longitudinally grooved, a block slideable between the cross-bars and also adjustable vertically therebetween, downwardly and outwardly inclined spring-fingers carried by the block and working in the 75 grooves of the cross-bars, and a cutter-blade depending from the block and coöperating with the top of the reservoir as a bed.

15. In an apparatus of the character described, a paper-roll holder, a paste-applying 80 device, a paper-support located between the paper-roll holder and the paste-applying device, a swinging frame working toward and away from the paper-support and including spaced cross-bars having longitudinal grooves, 85 and a cutter slidably adjustable between the cross-bars, coöperating with the paper-support as a bed and provided with spring-fingers working in the grooves of the cross-bars.

16. In an apparatus of the character described, a casing, a paper-roll holder, a pasting device, a paper-support located between the roll-holder and the pasting device, a frame hinged to the casing and working toward and away from the paper-support, a presser-roller 95 carried by the free end of the frame in coöperative relation with the pasting device, and a cutter carried intermediately by the frame and coöperating with the paper-support as a bed.

17. In an apparatus of the character described, a paper-roll holder, a pasting device, a paper-support located between the roll-holder and the pasting device, a frame adjustable toward and away from and located above 105 the paper-support, a cutter carried by the frame and coöperating with the paper-support as a bed, an upstanding paper-guide carried by the paper-support and located between the cutter and the roll-holder, and a paper-guide 110 pendent from the frame and located between the cutter and the upstanding guide.

18. In an apparatus of the character described, a casing, a paste-supply reservoir dividing the casing into a paper-compartment and a working paste-compartment, a paper-roll holder for the paper-compartment, a pasting device for the paste-compartment, the top of 115 the reservoir constituting a support for the paper in its passage from the roll-holder to the pasting device, a swinging frame hinged to the top of the casing and extending across the reservoir, a presser-roller carried by the free end of the frame and in coöperative relation with the pasting device, a cutter adjustable transversely across the frame and coöp- 120 125

erating with the top of the reservoir as a bed, a paper-guide rising from the reservoir between the cutter and the roll-holder, and a pendent paper-guide carried by the frame and 5 located between the first-mentioned guide and the cutter.

In testimony that I claim the foregoing as

my own I have hereto affixed my signature in the presence of two witnesses.
